ROOF SUPPORT FOR FLOATING ROOFS

Fred L. Goldsby and Frederick D. Moyer, Chicago,
Ill., assignors to Chicago Bridge & Iron Com-
pany

Application October 29, 1945, Serial No. 625,398

3 Claims. (Cl. 220—26)

1

This invention relates to a floating roof tank, and particularly to a roof support for such a tank whereby the roof may be supported above the bottom of the tank at the lowest position of the roof.

The floating roofs of floating roof tanks rise and fall as the quantity of liquid within the tank is varied. It has been found advisable to provide supporting means so that the bottom of the roof will rest some distance above the bottom of the tank when the tank is substantially empty. The support is particularly advisable when an internal drain is used for the floating roof to drain off accumulated water or the like from the top of the roof. The supports serve to protect the internal drain line when the roof is in its lowest position. These drain lines are usually made of pipe with rotatable connections or of flexible hose. The internal drains are connected to a sump on top of the roof and pass down through the contents of the tank to the outside shell of the tank. The drain must be long enough to extend between these points when the roof is in its highest position. As the roof falls to its lowest position the drain will rest on the bottom of the tank in coiled or folded position. It is necessary that the roof support does not interfere with the movement of the drain as the roof rises and falls.

We have invented a support for a floating roof tank that will support the roof in level position on the bottom of the tank and that will not interfere with the movement of the drain. This support comprises at least three vertical pipe-like members extending through the roof a substantial distance above and below the roof. The members are substantially equally spaced around the circumference of a circle whose center is substantially at the center of the roof. Each of the pipe-like members is braced against lateral and longitudinal movement by bracing extending from the bottom portion of the member to the bottom surface of the roof. It is preferred that there be also provided a foundation structure under each pipe-like member upon which the bottom end of the member will rest when the roof is in its lowest position. Each foundation structure comprises rigid plates supported above the bottom of the tank and substantially parallel thereto. These plates are preferably on a level with each other so that the roof will be supported in horizontal position.

The invention will be described as related to the embodiment shown in the accompanying drawings. Of the drawings Fig. 1 is a plan view of a floating roof tank embodying the invention;

2

Fig. 2 is a vertical section taken substantially through the center of the tank; Fig. 3 is an enlarged elevation of one of the supports for the floating roof; Fig. 4 is a horizontal section taken along line 4—4 of Fig. 3; Fig. 5 is a vertical section taken along line 5—5 of Fig. 3; and Fig. 6 is a plan view of one of the foundation supports upon which a pipe will rest when the tank is in its lowest position.

10 The floating roof tank shown in the accompanying drawings includes an outer shell 10 containing a liquid 11 with a roof 12 floating on top of the liquid. The roof 12 floats because of an air pontoon 13 of annular shape forming the circumference of the roof. This pontoon may be subdivided into sections. At the lowest point on the surface of the roof, which will usually be at the center, there is located a sump 14, with the bottom of the sump extending below the roof. 15 This sump is to collect water that falls on top of the roof. Extending from the sump to the outer shell 10 is a drain 15. The shell end 16 of the drain is located near the bottom of the shell. The drain 15 comprises a pipe 17 communicatingly attached to the sump 14 and extending along the bottom of the roof substantially parallel thereto. At the other end of the pipe 17 there is attached a flexible hose 18 of rubber or the like, and this hose extends to the shell 10 and has an outlet end 16.

20 As the roof falls the flexible hose 18 is laid along the bottom of the tank and forms curves. It is necessary to support the roof so that the hose will not be kinked. The support for the roof includes three vertical hollow pipes 19 extending through the roof a substantial distance above and below and open at both ends. These pipes are spaced around the circumference of a circle whose center is substantially at the center 25 of the roof. The vertical pipes form substantially an equilateral triangle, and each pipe is located near the pontoon 13. Each pipe 19 is hollow and has a threaded upper end onto which is screwed a collar 33. There is a vertical extension pipe 20 held within the hollow pipe 19 and extending beyond the ends of pipe 19. This vertical extension is capable of being fastened to the pipe in a plurality of positions. As shown the vertical extension 20 may be fastened to the 30 pipe 19 by means of holes 21 in the extension arranged for alignment with holes 22 at the top of the collar 33. The extension has two pairs of holes 21, while the collar has one pair of holes 22. The holes 21 and 22 may be aligned together 35 and the two pipes fastened together by means of

a bolt 32 passing through both pairs of holes. At the top of extension 20 there is provided a closure plate 23 and an upstanding ring 24 attached to the closure plate. The ring 24 on each extension may be engaged by hoisting means to lift the roof in constructing or repairing the tank.

The distance from the roof to the tank bottom may be varied by varying the distance from the roof to the bottom ends of vertical extension pipes 20. In constructing the roof this can be done by locating the point of attachment of the hollow pipes 19 to the roof 12 at any desired distance from the bottom of pipes 19. Further variation may be accomplished when the tank is in use by turning threaded collar 33 to extend or retract it. If desired, more than two sets of holes 21 may be provided in the extension pipes 20.

Each vertical pipe 19 is braced against lateral and longitudinal movement by bracing extending from the bottom portion of the pipe to the bottom surface of the roof. This bracing, as shown, comprises a plurality of circular rods 25 extending from near the bottom of the pipe to the bottom surface of the roof with the bottom ends lying along the circumference of a circle whose center is substantially at the center of the pipe. The bracing may also be plate webs if desired. The rods 25 are welded or otherwise fastened to the pipe and to the roof, and are spaced equally around the circle. The bracing also includes an annular plate 26 substantially concentric with the pipe and attached to the bottom surface of the roof and to the outer surface of the pipe. Spaced around the annular plate are triangular blocks 27 fastened to the pipe and to the annular plate.

The bottom end of pipe 20 is rounded and is adapted to rest on a platform 28 when the roof is in its lowest position. This platform comprises a circular plate 29 rigidly supported above the bottom surface of the tank on beams 30 arranged at right angles to each other. Between each adjacent pair of beams 30 there are located connecting beams 31 substantially forming an inscribed square within the circle of the circular plate 29. This arrangement of beams serves to hold the plate 29 rigid and to give full support to the pipe 20. The pipe rests either on the center of the circular beam or out toward the edge.

As the pipes 20 and the platforms 28 are equally spaced around the tank the roof 12 will be maintained level at all times. As many pipes and platforms may be used as desired, depending in part upon the size of the tank and the degree of rigidity desired.

The rounded bottom ends of pipes 19 are important features of the invention as they push aside the drain hose 18 when the roof approaches the bottom of the tank and thus prevent crushing the hose. They are also important as they penetrate any ice formation on the bottom of the tank. When the pipes 19 are resting on the supports and water in the bottom of the tank freezes it is easier for the pipes to tear loose from the ice when the bottom ends are rounded.

The support plates 29 are shown as circular in shape but they may also be square or any other desired shape. They are preferably all arranged essentially on a level with each other so that

the roof will rest in horizontal position on the bottom of the tank. Final adjustments may be made to achieve this horizontal position by turning collar 33 to a desired position and by locating the holes 21 wherever desired. The support rods 25 serve not only to brace the hollow pipe 19 and thus extension pipe 20 but also as fenders to keep hose from catching around the bottom ends of the pipes. This fending action is due to their sloping arrangement.

The roof support shown and described herein is useful on any type of floating roof.

Having described our invention in considerable detail as related to one embodiment of the same, it is our intention that the invention be not limited by any of the details of description unless otherwise specified, but rather be construed broadly within its spirit and scope as set out in the accompanying claims.

We claim:

1. A roof support for a floating roof tank comprising at least three hollow vertical pipe-like members extending through the roof a substantial distance above and below the roof and substantially equally spaced about the circumference of a circle whose center is substantially at the center of the roof, each of said pipe-like members being braced against lateral and longitudinal movement by bracing means extending from the bottom portion of the member to the bottom surface of the roof, a collar threaded to the upper portion of each of said members and having an opening therein, an extension extending through said collar and through said member and having a plurality of openings therein spaced longitudinally of the extension, and a pin insertable through the opening in the collar and one of the openings in the extension to secure the extension to the collar, said extension having a bottom end extending below the pipe-like member to support the roof above the bottom of the tank.

2. The roof support of claim 1 in which the bottom end of said extension is rounded and including a foundation structure under each extension upon which the bottom end of the extension pipe will rest when the roof is in its lowest position, said foundation structure comprising rigid plates supported above the bottom of the tank and substantially parallel thereto.

3. The roof support of claim 1 in which said extension is provided with a fastening ring at its top end to which a hoisting mechanism may be attached.
